US0D1017321S

(12) **United States Design Patent** (10) **Patent No.:** **US D1,017,321 S**
(45) **Date of Patent:** **** Mar. 12, 2024**

(54) **COFFEE GRINDER HANDLE**

(71) Applicant: **Shenzhen Fanpuguiwen E-Commerce Co., Ltd.**, Guangdong (CN)

(72) Inventor: **Zhaoyang Tian**, Guangdong (CN)

(73) Assignee: **Shenzhen Fanpuguiwen E-Commerce Co., Ltd.**, Guangdong (CN)

(**) Term: **15 Years**

(21) Appl. No.: **29/894,038**

(22) Filed: **Jun. 5, 2023**

(30) **Foreign Application Priority Data**

Jun. 2, 2023 (EM) 015023345-0001

(57) **CLAIM**

The ornamental design for a coffee grinder handle, as shown and described.

DESCRIPTION

FIG. 1 is a front, right and top perspective view of a coffee grinder handle, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the coffee grinder handle in a folded state.

The broken lines depict environmental structure that form no part of the claimed design.

1 Claim, 9 Drawing Sheets
